ART OF SCANNING AND REPRODUCING
MATTER

Robert E. Naumburg, Cambridge, Mass.

Application April 10, 1931, Serial No. 529,037

7 Claims. (Cl. 197—6.1)

This invention relates to scanning apparatus for use in various arts and particularly to a method of reproducing ordinary type printing and other printed matter in a form suitable for touch reading by blind people. In certain aspects the invention is related to the subject matter of my copending application Serial No. 305,293, September 11, 1928 and in so far as possible the present drawings and description do not repeat the features common to the two inventions.

The principal objects of the present invention are to provide a way of rapidly and economically reproducing printed matter for touch reading which can readily be practiced by blind people so that their reading need not be confined to the limited amount of printed matter published in Braille and the like but may be extended to any and all printed matter at moderate cost and to reproduce the printed matter in a form such as Braille, Moon type and other embossed type with which many blind people are familiar and by which the reader may comprehend a letter or group of letters by a single touch sensation. Other objects are to facilitate the initial positioning of each page or line of printed matter by the sense of touch preparatory to reproducing the page or line; to vary the size of the reproduced characters at will; to afford a rapid rate of reproduction with little delay in shifting to successive lines; to afford means for reading printed matter by touch without reproducing the matter, preferably without disturbing the reproducing means in case such means are incorporated; to avoid false indication or reproduction, particularly while shifting from one line to the next succeeding line; to provide an improved scanning disk useful for blind reading and other purposes; to provide inexpensive reproduction, with a medium which can be used repeatedly as a temporary record and/or can be readily converted into a permanent record; and generally to improve the art to which this invention relates.

For the purpose of illustrating the genus of the invention a typical embodiment is shown in the accompanying drawings in which

Fig. 1 is a top plan view;

Fig. 2 is a partial front elevation;

Fig. 3 is a diagrammatic view illustrating the scanning disk;

Fig. 4 is a top plan of the reproducing and/or feeder mechanism;

Fig. 5 is a side elevation of this mechanism;

Fig. 6 is a circuit diagram;

Fig. 7 is a face view of the reproducing medium

with typical characters reproduced thereon; and Fig. 8 is a section of the reproduction sheet shown in Fig. 7.

The particular embodiment of the invention chosen for the purpose of illustration comprises two groups of mechanism, the one at the left-hand side of Fig. 1 cooperating with the book or other printed sheet to produce current variations corresponding to the printed characters and the other, shown at the right-hand side of Fig. 1, reproducing the printed matter on sheet material in the form of Braille characters in response to the current variations. The first group of mechanism for scanning the subject matter is, with certain exceptions referred to hereinafter, essentially the same as disclosed in the aforesaid application.

In general this scanning mechanism comprises a support 1 (preferably such as shown in said application) for supporting a book or other printed matter in horizontal position, a glass cover plate 2 for holding the exposed pages of the book substantially in a horizontal plane, a bracket 3 carrying a half nut 4 meshing with a worm 5 for advancing the book one line at a time in response to a ratchet handle 6, the book carriage being retracted to start a new page by lifting the half nut 4 out of engagement with the worm 5 and reengaging the nut at a different location of the worm. The optical mechanism is mounted on a carriage 7 reciprocatable back and forth from left to right on the stationary guide 8, the carriage having a rack 9 meshing with pinion 10 on shaft 11. The optical parts comprise a light source 12, three lenses 13, 14 and 15, the lens 15 being adjustable longitudinally of the optical axis by means of a rack 16 and a pinion 17 to accommodate letters of different sizes, a continuously rotating scanning disk 18, a right-angle reflecting prism for reflecting the light rays downwardly, lenses in the vertical portion of the optical path, these lenses being mounted as indicated at 20 in Fig. 2, and a selenium cell 21 mounted on the support 20 to receive the light reflected from the printed page, the cell having a central opening 22 to permit the passage of the light rays to the printed page as fully disclosed in the aforesaid application.

As illustrated in Fig. 3 the scanning disk 18 breaks up the light into six intermittent beams or rays which are incident to the printed page along lines *a*, *b*, *c*, *d*, *e* and *f* spaced to intersect the letters as indicated. According to this invention the dimensions, longitudinally of the row, of the perforations in the scanning disk and the

spaces therebetween, are approximately equal, whereby the current variations produced in the electrical circuit later to be described are approximately sinusoidal. The perforations of each row are also staggered transversely of the row, preferably to such extent that the inner edges of alternate perforations lie approximately in the same line. In this way the scanning lines *a*, *b*, *c*, *d*, *e* and *f* more constantly intersect the desired portions of the letters notwithstanding inaccuracy in the alignment of the letters, without undesirably increasing the width of the perforations transversely of the rows. Moreover, for reasons not fully understood, the feelers or strikers hereinafter described operate more uniformly and reliably if the perforations are staggered.

The reproducing mechanism shown at the right-hand side of Fig. 1 and illustrated more in detail in Figs. 4 and 5 comprises a carriage 23 reciprocatable back and forth from left to right on rollers 24 (Figs. 4 and 5) which roll on stationary guides 25. The carriage has a projecting arm 26 threaded to mesh with a worm 27 for reciprocating the carriage back and forth. Mounted on the carriage 23 are six electromagnets 28*a*, 28*b*, 28*c*, 28*d*, 28*e* and 28*f* which are controlled by the light rays scanning along the lines *a*, *b*, *c*, *d*, *e* and *f* (Fig. 3) respectively. Each magnet has an armature 29 held in retracted position by a spring 30, the retracted position being adjustable by a screw 31. Pivotally connected to the free ends of the armature levers 29 are vertical rods 32 which are guided in their up and down motion by an upward extension 33 of the carriage 23. The upper ends of these rods are rounded to constitute strikers or feelers as hereinafter described. As shown in Fig. 5 the second, third and sixth of these rods (counting from left to right) are in elevated position and the other three are in the lowered position occupied when the corresponding magnets are energized.

The sheet material to be embossed by the strikers 32 is fed from a roll 34 upwardly and rearwardly around a curved guide 35 having, in its upper horizontal portion, an elongate slot 36 corresponding to the path of reciprocation of the strikers 32. The sheet material *S* is fed upwardly and to the rear by means of rollers 37 and 38, the lower rollers 37 being mounted on shaft 39 and the upper rollers 38 being mounted on arms 40 pivoted to swing upwardly about the shaft 41 journaled in brackets 46. While a line of characters is being embossed on the sheet *S* by the strikers 32 the portion of the sheet bridging the elongate slot 36 is held taut by pressure pads 42 and 43 which are preferably fared with chamois skin. The pad 42 is supported at each end by a bracket 44 fast to the shaft 41 (Fig. 1). And the pad 43 is supported by a plate 45 fast in a slot in the shaft 41. Thus when the shaft is rotated in a counterclockwise direction (Fig. 5) both pressure pads are lifted from the sheet *S*. The mechanism for rotating the shaft 41 comprises a lever arm 47 fast to the end of the shaft (Fig. 1) and linkage 48 interconnecting the arm 47 with the handle 6. This linkage comprises a rod 49 which carries a pawl for rotating the shaft 39 of the lower feed rolls 37 through a ratchet wheel 50 fast on the end of the shaft.

The reciprocating scanning carriage 7 and the reciprocating reproducing carriage 23 are actuated synchronously by motor 51 which continu-

ously drives shaft 52 by a belt 53. The worm shaft 27 carries a friction disk 54 which cooperates with a friction roller 55 threaded on the shaft 52 to screw back and forth between two limiting positions near the center and periphery of the disk 54 respectively. The motor 51 is a reversible motor and suitable means (not shown) controlled by one of the reciprocating carriages or associated parts are provided for stopping and/or reversing the motor at each end of the reciprocatory movement of the carriages. While the carriages are advancing from left to right the roller 55 engages the disk 54 near the periphery of the latter as shown in Fig. 1 to produce relatively slow movement of the carriages and during the reversed travel of the carriages from right to left the roller 55 engages the disk 54 near the center of the disk to produce a quick return of the carriages, it being understood that when the motor 51 is reversed the roller 55 automatically threads along the shaft 52 from one of its extreme positions to the other. The worm shaft 27 which drives the reproducing carriage 23 is interconnected with the shaft 11 which drives the scanning carriage 7 through gearing 56 and a clutch 57, the clutch being provided to disconnect the scanning carriage while the latter is being initially adjusted at the beginning of a new page or sheet of printed matter.

The circuit arrangement illustrated in Fig. 6 is substantially the same as that disclosed in the aforesaid application in which 21 is the selenium cell connected through an amplifier to a circuit containing transformer primaries A, B, C, D, E and F corresponding to the similarly designated lines of Fig. 3 and magnets of Figs. 4 and 5. With each primary is associated a secondary circuit tuned to one of the frequencies determined by the number of perforations in each row of the scanning disks (the numbers preferably being 85, 71, 59, 47, 37 and 29 counting from the periphery of the disk toward the center) one such secondary being shown in association with primary A. Each of the six secondary circuits comprises a tuning condenser C', a three-element vacuum tube V, a feed-back coil B' and a relay through which the corresponding magnet 28 is actuated. This relay is preferably of the trigger type (such as the General Electric thyratron) which effects quick and large current changes in the magnet 28 in response to slight current variations in the input circuit. The use of regeneration in the filter circuit serves to emphasize the desired frequency to the exclusion of others. When the scanning rays are incident to white paper or other reflecting surface the flow of current increases in the selenium cell, also in the trigger tube and also in the magnet 28, thereby retracting the corresponding striker 32. When the scanning rays are incident to a printed line or other non-reflecting surface comparatively little current flows through the selenium cell and consequently the trigger tube completely stops the flow of current through the magnet 28, thereby permitting the spring 30 to advance the corresponding striker 32.

Thus it will be evident that the six (more or less) intermittent light beams produce in the selenium cell circuit a composite current comprising six superposed waves and that the tuned circuits filter out the six waves into the individual circuits containing the trigger tubes or other devices for manifesting current variations. It will also be understood that any suitable filter system

may be employed including tuned relays or magnets.

From the foregoing it will be understood that a line of printing is reproduced on the sheet S in the form of raised characters in the following manner. When one of the six light rays or beams crosses a black line the corresponding striker 32 is advanced to produce an indentation in the sheet S. If the printed line be vertical and relatively thin the striker is advanced only momentarily to produce a dot on the sheet S. If the line of the printed character extends horizontally for a considerable distance, such as the top of a capital T, the striker is held in advanced position for a considerable interval of time depending upon the length of the line, thereby producing in the sheet S an indentation in the form of a dash. Thus the letters o, f, t are reproduced in the form illustrated in Fig. 7.

The reproducing carriage is preferably advanced at a rate several times as fast as that of the scanning carriage in order to permit enlargement of the characters horizontally (as well as vertically) and in order to increase the spacing between the embossed characters for more facile reading by touch. For the purpose of still further increasing the spacing between the embossed characters, particularly where the embossing is in the form of dashes rather than dots, I preferably provide means whereby each striker 32, when indented into the sheet S, may lag behind the reproducing carriage 23 until it is withdrawn from the sheet, whereupon it snaps forward to regain its normal position relatively to the carriage longitudinally of the path of travel of the carriage. In the illustration this gap widening means comprises guide slots 60 (Fig. 4) in the carriage extension 33, the slots extending longitudinally of the path of travel of the carriage and the strikers 32 being pivoted on the lever arms 29 to swing lengthwise of these slots, spring 61 being provided normally to hold the strikers at the forward ends of the slots and to snap the strikers back to these ends when retracted from the stationary sheet S. This arrangement has the further advantage that thick and thin lines as, for example, vertical strokes of different shading, are reproduced with approximately equal thickness, this fact affording, according to actual experience, an instrumental aid to the blind in reading the embossed sheets.

The sheet S is preferably in the form of aluminum or other metal foil about two-thousandths of an inch thick embossed with minute protuberances which project about one-thousandth of an inch and which are much smaller in transverse dimensions than the corresponding dimensions of the rounded noses of the strikers 32 (e. g. 100 to the inch), whereby the sheet has substantially no tendency to rupture when impacted by the strikers 32 particularly when indented by the strikers oppositely to the protuberances. By using such embossed foil the sheet may be indented by the strikers 32 merely by folding the sheet taut in the region of the strikers and without backing the sheet with a platen. Consequently the embossed characters of the sheet are accessible for touch reading by the operator as soon as they are formed. Thus the operator may read the characters as they are being reproduced and after the roll of foil is exhausted it may be ironed out for repeated use. By ironing out the foil with mandrels having embossing protuberances the aforesaid minute pro-

tuberances may be reembossed in the foil in the ironing process.

On the other hand if the sheet of embossed characters is to be preserved for repeated use the characters may be permanently upheld by applying to the sheet a composition which sets when dry. Any one of many compositions may be employed depending upon the degree of permanency desired. Typical examples are shellac, plastic wood and tile cement dissolved in plastic wood solvent. The composition is preferably applied to the back of the sheet and when using plastic wood or the like the indentations may be largely or entirely filled.

Instead of using foil I may use a fine mesh screen, preferably comprising several superposed registered sheets or bands of screening, with pins snugly fitting in the screen perforations so that they may be engaged by the strikers to project beyond the face of the screen. Preferably these pins normally project from the rear of the screen for engagement by the strikers so that the strikers need not enter the perforations. For repeated use the pins may be pressed back into the screen by a roller or the like; and the screen (as well as foil) may be in the form of an endless belt which is rolled in advance of the striker path for repeated use.

The width of the sheet S and its position relative to the path of travel of the reproducing carriage 23 is preferably such that the strikers 32 are exposed at one or both sides of the sheet at one or both ends of each reciprocation, preferably at the left hand end, whereby the tips of the strikers may be touched directly by the tip of the finger while initially adjusting the position of the lines of printed matter relative to the path of reciprocation of the scanning carriage. It is also desirable to provide manual control means for the motor whereby the carriages may be reversed at any point in their travel.

In order to prevent the strikers 32 from operating on the return stroke of the carriages from right to left means may be provided to render the electrical devices unresponsive to the printed matter during the reverse movement. The preferred means, illustrated in Fig. 2, comprises a reflecting shutter 70 mounted on arms 71 to swing back and forth about the pivot 72. Also fast to the pivot pin 72 is a second arm 73 the lower end of which slides over a soft track 74 of rubber or the like on a stationary guide 8. The distance between the pivot 72 and the face of the soft track 74 is somewhat less than the length of the depending portion of the arm 73. Thus when the carriage reverses its movement the arm 73 gouges into the soft track and is caused to swing past dead center to a corresponding position on the other side of the vertical plane of the pivot therein and then slide freely over the surface of the soft track until the carriage is again reversed. As shown in Fig. 2 the carriage is traveling to the left and the light is continuously reflected from the shutter to the light sensitive cell, thereby maintaining magnet 28 energized during the return movement. When the carriage reaches the left end of its path of reciprocation and reverses, the reflecting shutter automatically swings to the left out of the path of the light rays. This shutter preferably has a diffusing surface instead of a mirror surface, ordinary white paper or cardboard being suitable.

I claim:

1. Apparatus for embossing sheet material comprising means for holding the sheet at each

- side of an elongate space, strikers for indenting the sheet at points distributed transversely of said space, and means for producing relative movement between the strikers and sheet longitudinally of said space, said strikers being yieldingly mounted to follow said movement while indented in the material. 5 characters legible through the sense of touch, which comprises holding the sheet material taut between locations spaced along the surface of the sheet and indenting the sheet between said locations, the tautness counteracting transverse displacement of the sheet by the indenting impacts. 80
2. Apparatus of the character referred to for embossing material, comprising a striker for indenting the material, and means for producing relative movement between the striker and material, the striker being yieldingly mounted to follow said movement while indented in the material. 10 6. Apparatus for indenting sheet material from one side to form on the other side raised characters which may be read through the sense of touch, comprising means for holding the sheet material taut and means for indenting the taut material, the latter side of the sheet being unobstructed adjacent the indenting means so that the characters may be read by touch during the process of forming the characters. 85
- 15 3. Apparatus of the character referred to for embossing material, comprising a striker for indenting the material, means for producing relative movement between the striker and material, the striker being pivotally mounted to follow said movement while indented in the material, and a spring for returning the striker to normal position when disengaged from the material. 20 7. Apparatus of the character referred to comprising means carrying sheet material, an indenting striker relatively moving along the surface of said sheet material and yieldable in the direction of said relative movement, whereby said relative movement is interrupted if said striker contacts with said sheet material, means limiting said yielding motion, whereby said relative movement is resumed upon said striker contacting 90 with said limiting means after a certain period of time, and means for returning said striker to normal position upon interruption of its contact with said sheet. 95
- 25 4. The method of indenting sheet material from one side to form on the other side raised characters legible through the sense of touch, which comprises holding the sheet material taut and indenting the taut material, whereby the raised characters may be read by the sense of touch during the process of forming the characters. 100
- 30 5. The method of indenting sheet material from one side to form on the other side raised characters legible through the sense of touch, which comprises holding the sheet material taut and indenting the taut material, whereby the raised characters may be read by the sense of touch during the process of forming the characters. 105
